R. HAWKINS.
GRAIN SCREEN.

No. 66,333.

PATENTED JULY 2, 1867.

ONLY DRAWING ACCESSIBLE
TAKEN FROM PATENT OFFICE REPORT
1867 - VOL. III.

United States Patent Office.

REASON HAWKINS, OF PALESTINE, INDIANA.

Letters Patent No. 66,383, dated July 2, 1867.

GRAIN-SCREENS.

The Schedule referred to in these Letters Patent and making part of the same.

TO ALL WHOM IT MAY CONCERN:

Be it known that I, REASON HAWKINS, of Palestine, Sugar Creek Post Office, Hancock county, Indiana, have invented a new and useful Improvement in Grain-Screens; and I do hereby declare that the following is a full, clear, and exact description thereof, which will enable others skilled in the art to make and use the same, reference being had to the accompanying drawings forming part of this specification, in which—

The drawing represents a longitudinal vertical section of my improved grain-screen.

This invention relates to an improvement in the construction of screens for separating the trash and foul seeds of cockle and cheat from wheat and other small grain, and dividing the grain into first and second qualities.

The machine is very simple and cheap in its construction, and is suited to the use of farmers generally for cleaning and assorting their grain before sending it to mill or market.

A is a long box, made higher at one end than the other, and supported on four posts B B', which project above the top. In the box is a drawer, M, divided into two compartments by a cross-partition, b. On the top of the posts B' is set a hopper, C, which opens below upon an inclined board, c, over which is placed an adjustable cross-bar, d, for regulating the quantity of grain allowed to pass. The incline c is swivelled to the posts B' at the upper end. The grain falls from the hopper on the incline c, and passing under the cross-bar d falls directly upon the trash-screen e, placed horizontally, or nearly so, and made of coarse wire netting, to allow all the grain to pass through and throw off only the chaff and other light stuff over the head of the machine on which its rests. An inclined open box, D, is suspended at the lower end to the posts B, on pivots g g, in slots or elongated holes in the posts, the head of the box being placed under the trash-screen e, and resting on the roller E, while the lower end projects over the end of the box A. A screen, h, is made of strong wire, with a mesh small enough to prevent the full-sized grains of the best quality from passing through, and is fastened in the open box D from end to end; and across the box are placed five cross-bars k k, more or less. The lower side of the bars is set just far enough above the screen h to allow the grain to pass the bars while they retard its forward movement over the screen, so as to sift out all the smaller and inferior grains which pass through the screen while the superior grain is discharged at the foot of the screen. Another screen, m, is made of finer wire, and smaller meshes, and is placed a few inches below the screen h. It extends from the head of the box D nearly to the bottom, and terminates over one of the compartments in the drawer M, for discharging the inferior second quality of grain therein, while the cheat, cockle, and other foul seeds and dirt fall through the screen directly into the other compartment in the drawer M. The box D is provided with a floor, n, that extends down from the head to discharge what foul seeds fall through the upper part of the screen m into the drawer. The screen-box D is supported by the floor n upon the octagonal roller E hung in the posts B' B', which is turned by a crank, p. The screens have an oscillating or vibratory motion for the purpose of sifting the grain, the operation of which is manifest.

Having thus described my invention, what I claim as new, and desire to secure by Letters Patent, is—

The arrangement of the screens h and m, and the cross-bars k k, in the box D, and the trash-screen e, at the head of the box, in combination with the octagonal roller E, operating as and for the purposes herein described.

The above specification of my invention signed by me this 4th day of March, 1867.

REASON HAWKINS.
